CLAIM

The ornamental design for a combined electric foot and calf massager, as shown and described.

DESCRIPTION

FIG. 1 is a front, left side perspective view of a combined electric foot and calf massager with leg extended.

FIG. 2 is a back, right side perspective view of a combined electric foot and calf massager without leg extended.

FIG. 3 is a back view of a combined electric foot and calf massager.

FIG. 4 is a front view of a combined electric foot and calf massager.

FIG. 5 is a front, bottom perspective view of a combined electric foot and calf massager.

FIG. 6 is a right side view of a combined electric foot and calf massager.

FIG. 7 is a left side view of a combined electric foot and calf massager.

FIG. 8 is a top plan view of a combined electric foot and calf massager.

FIG. 9 is a bottom plan view of a combined electric foot and calf massager with leg extended.

FIG. 10 is a bottom plan view of a combined electric foot and calf massager without leg extended; and,

FIG. 11 is a bottom, right side perspective view of a combined electric foot and calf massager with leg extended.
